ATTY.

UNITED STATES PATENT OFFICE.

JESSE V. WISE, OF OAK PARK, ILLINOIS, ASSIGNOR TO THE RICHARDS MANUFACTURING COMPANY, OF AURORA, ILLINOIS.

FIRE-DOOR-RELEASING DEVICE.

No. 893,047.

Specification of Letters Patent.

Patented July 14, 1908.

Application filed March 12, 1906. Serial No. 305,473.

To all whom it may concern:

Be it known that I, JESSE V. WISE, a citizen of the United States, residing at Oak Park, in the county of Cook and State of Illinois, have invented certain new and useful Improvements in Fire-Door-Releasing Devices, of which the following is a specification.

This invention relates to improvements in means for automatically releasing and closing doors of the class known as "fire-doors", and especially to means adapted to become operative through the melting of fusible links when the temperature surrounding the door 15 is raised to the fusing point of such devices.

The especial object of the improvements which form the subject-matter of this application is to provide means that can be readily applied to slidable fire doors of the usual 20 construction and arrangement, and that will automatically and simultaneously release the doors on both sides of the door way or opening when fire is present on either side of the wall in which such opening is provided.

25 A further object is to provide means that will facilitate the ordinary opening and closing of the doors, and in which all the parts are exposed and are of simple mechanical construction.

30 In the accompanying drawing which forms a part of this application I have illustrated a preferred adaptation of my invention in the following views:—Figure 1 shows in elevation, a portion of a fire-wall upon which is 35 erected a fire-door of ordinary construction to which is applied my invention. Fig. 2 is a detail on an enlarged scale of a part of my invention. Fig. 3 is a cross section taken through the wall 3 of Fig. 1 at a point just 40 above the wires 20—20^a.

Referring to the details of the drawing, 3 represents a brick fire-wall in which a doorway or arch 4 has been provided. Projecting from the top of the wall are joists 5, and 45 secured to the face of the wall are an inclined door-hanger track 6, door stops 7 and stay-roller 8, all of which are of well known construction and arrangement.

Slidably mounted on the track by hangers 50 9 and adapted to move by gravity to a closed position is a fire-door 10 of sheet-metal, from one edge of which projects an arm 11.

Secured at the upper or left-hand (as shown) end of the track by a set-bolt 12, is an

iron plate 13, in the center of which is a stud-bolt 14 which projects outwardly at right angles from the plate. On the stud-bolt is mounted a grooved pulley 15, and between the pulley and the bolt-head is placed an iron strap 16 the edges of which are slightly grooved at two points to receive loops 17 and 18 formed respectively on the ends of ropes or wires 19 and 20. The rope 19 passes under a pulley 21 secured to a weight 22 then passes over the pulley 15 and has its other end fastened to one member of the fusible link 23, the other member of which is connected by a short rope to the outer end of the arm 11. The weight 22 holds the door open against gravity.

70 The rope 20 passes over a pulley 26 suspended from one of the joists 5, and has its end secured to one member of the fusible link 24, the other member of which is secured to a rope 20^a which passes over the swivel-pulley 75 27 which is suspended from another joist 5. The rope 20^a after leaving the pulley passes through a hole 25 formed through the wall 3, and it is connected with another swivel pulley (not shown) on the opposite side of the 80 wall where the construction and arrangement of all parts described are duplicated.

The object in placing the fusible link 23 near the edge of the door is to subject it to heat that would be likely, because of the 85 draft, to pass through the doorway in case of fire on either side of the wall 3. It will be apparent that when the link 23 fuses, the rope 19 will be relieved of the downward tension exerted by the weight 22 hence the weight 90 22 will fall to the floor whereupon the outer end of the strap will be pulled upwardly by the rope 20 until the loop 17 slides from the end of the strap, thus entirely releasing said rope and permitting the same action by the parts 95 on the opposite side of the wall.

If the link 24 should fuse first instead of 22 and thus release rope 20, the outer end of the strap 16 will be pulled downward by the weight 22 thus permitting the loop 17 to slide 100 from the strap, and push off loop 18, thereby release door 10 and the correspondingly arranged and connected door on the opposite side of the wall.

It will be understood that the closing of 105 the door by sliding on the track 6 may be through gravity or through mechanical means applied thereto in any of the well

known constructions, the same forming no part of this invention which pertains to releasing means alone.

This invention is designed to meet the requirements of boards of fire underwriters covering the use of fire-doors on both sides of wall openings and the automatic closing of such doors when fire is present on either side of such openings, and so far as I am aware I am the first to devise means that comply with this requirement. I therefore do not wish to be limited to the exact construction shown but

What I claim is:—

- 15 1. In combination with a wall having an opening therein and slidable closures arranged on opposite sides of said wall, means for holding each of said doors in its open position, said means comprising a rope connected with the door, and with a pivoted bar, and carrying a tension device and a fusible link, said tension device and link being arranged on the side of the wall to which said closure is applied, and means connecting the pivoted bar of one door with the pivoted bar of the other door, said means comprising fusible links on opposite sides of said wall.
- 20 2. In combination with a wall having an opening therein and slidable doors arranged on opposite sides of said wall, means for holding each of said doors in its open position, said means comprising a rope connected with the door and removably connected with a pivoted bar, said rope carrying a weight, and a fusible link arranged near the forward edge of the closure, and a second rope removably connected with the bars on opposite sides of said wall, and comprising fusible links arranged on opposite sides of the wall.
- 25 3. In combination, a hanger track, a slidable closure, a rope secured at one end to said closure and carrying a slidable weight and a fusible link, a pulley secured to said track and carrying said rope, and means holding said rope against the tension of said weight and door, said means comprising a lever mounted on the spindle of said pulley, and a rope connected with said lever and held under tension.
- 30 4. In combination, a hanger track, a closure slidably mounted on said track, means for holding said door in its open position said means comprising a pulley connected with said track, a rope including a fusible link, secured at one end to the door, arranged on said pulley, carrying a weight and having a loop at its free end, a pivotally mounted bar having its free end loosely engaged by said loop, and means for holding said bar in engagement with said loop, said means comprising a rope engaging said bar, and having a fusible link therein and held under tension.

5. In combination with a wall having an opening therethrough, a closure arranged when released to automatically cover said opening, holding means for said closure, comprising a fixed pulley, a rope arranged on said pulley and secured to said door and carrying a weight, a fusible link connected with said rope, and with the closure, a pivoted bar detachably connected with said rope and adapted to be depressed by said weight, a second rope connected with said bar, a fusible element connected with said rope, and means for holding said rope under tension counter to the tension on the first named rope.

6. In combination with a wall having an opening therethrough, closures arranged on opposite sides of said wall and adapted when released to automatically cover said opening, holding means for said closures comprising a rope slidably extending through said wall and having arranged therein a fusible link at a point on each side of said wall, a pivoted bar detachably connected with each end of said rope, and two weight-carrying ropes including fusible elements, each detachably connected to one of said bars, and secured to one of said closures.

7. In combination, a hanger-track, a closure slidably supported on said track, a fusible device connected with said closure, a rope connected with said fusible device, tension means connected with said rope, a pulley carrying said rope, a pivoted bar directly connected with said rope and pulley, a second rope directly connected with said bar and adapted to normally hold it against the tension means of the first named rope, and a fusible device connected with said second rope.

8. In door holding and releasing means, a pivoted bar, flexible and fusible means detachably connecting said bar and the door, a tension device carried by said means, and flexible means directly and detachably connected with said bar and adapted to normally hold it against said tension device.

9. In a door holding and releasing means, a pivoted bar, a rope directly connected with said bar, a weight carried by said rope, a fusible connection between said rope and the door, a second rope directly connected with said bar and adapted to normally hold it against said weight, and a fusible device connected with said second rope.

In testimony whereof I affix my signature in presence of two witnesses.

JESSE V. WISE.
